UNITED STATES PATENT OFFICE.

RICHARD C. LOWE, OF VIRGINIA, ILLINOIS.

COMBINATION STEP-LADDER AND IRONING-BOARD.

1,139,784.

Specification of Letters Patent. Patented May 18, 1915.

Application filed September 8, 1914. Serial No. 860,754.

To all whom it may concern:

Be it known that I, RICHARD C. LOWE, a citizen of the United States, residing at Virginia, in the county of Cass and State of Illinois, have invented certain new and useful Improvements in Combination Step-Ladders and Ironing-Boards, of which the following is a specification, reference being had to the accompanying drawings.

The object of this invention is an improved household article which may be used either as an ironing-board or as a step-ladder, the parts being simple in construction and comparatively few in number, and durable and not liable to get out of order.

A further object of the invention is a combined ironing-board and step-ladder, in which the pivotal section of the ladder portion of the device constitutes, with the remaining section thereof when properly adjusted, a secure support for the ironing-board.

The invention also has for an object a simple, durable and efficient construction of device of this kind, in which improved means are provided for holding the pivotal section of the ladder part of the device in operative relation to the remaining step providing portion when the device is used as a ladder, whereby the device will be stable and possibility of accidents precluded.

And the invention also aims to generally improve devices of this class so as to render them more useful and commercially desirable.

With these and other objects in view, as will more fully appear as the description proceeds, the invention consists in certain constructions, combinations and arrangements of the parts that I shall hereinafter more fully describe and claim.

For a full understanding of the invention, reference is to be had to the following description and accompanying drawing, in which,

Figure 1 is a perspective view of my device arranged as a step-ladder. Fig. 2 is a longitudinal sectional view thereof arranged as an ironing-board.

Corresponding and like parts are referred to in the following description and designated in all of the views of the accompanying drawing by like reference characters.

Referring to the drawing, the numeral 1 designates the stiles of the ladder portion A of my improved device, said stiles having

secured thereto, any desired number of relatively fixed steps 2, the stiles being provided on their inner faces above said fixed steps, with cut-out portions or recesses 3, as clearly illustrated in the drawing.

4 designates auxiliary stiles that are received in the recessed portions of the stiles 1 above the fixed steps 2, a pintle rod 5 extending through the stiles 1 from one to the other and also passing through the stiles 4 intermediate of the ends of the latter, whereby the stiles 4 and the steps 6 which they carry and which with the stiles, constitute a swinging frame B, may be aligned with the main stiles 1 or swung to the required angular relation thereto.

Preferably I provide turn buttons 7 which are secured to the rear edges of the stiles, but above the pintle rod 5, which may be turned over the adjacent edges of the stiles 4, so as to prevent the frame B from being accidentally displaced or swung out of its operative position when the device is used as a ladder, it being noted that the lower ends of the stiles 4 will abut against the upper surface of the uppermost fixed step 2 and will thereby coöperate with the turn buttons 7 for securely holding the frame.

The strut for the ladder A is in the form of an ironing-board and is designated C. It is connected to the top step or rung of the ladder A, by means of hinges 8 of any desired construction, and it is provided on one face and intermediate the ends thereof with a laterally elongated keeper 9 in the form of a loop, the same being designed to receive the hooked end 10 of a link bar 11, the latter being pivotally swung from a loop 12 that is secured to the underside of one of the steps 6 of the frame B adjacent the pintle rod 5.

From the foregoing description, in connection with the accompanying drawing, the operation of my improved combined ironing-board and step-ladder will be apparent. In the practical use of the device, when it is to be used as a ladder, the link bar 11 will be engaged with the keeper 9 and the frame B will be held in place with its stiles 4 in line with the stiles 1.

When the device is to be used as an ironing-board it is only necessary to release the frame B and to swing it into an angular relation with the ladder A which constitutes the main frame of the device, until an opening 6' in one end of the frame B comes in

registry with the keeper loop 9, whereupon the said loop is entered into said opening and the frame B is held in fixed relation to the ladder or main frame A, with the board 5 resting solidly upon one end of the first named frame.

While the accompanying drawing illustrates what I believe to be the preferred construction of my invention, it is to be understood that the invention is not limited thereto, but that various changes may be made in the construction, arrangements and proportions of the parts without departing from the scope of the invention as defined 15 in the appended claims.

What is claimed, is:

1. A combined ironing-board and step-ladder comprising a main frame, an auxiliary frame pivotally mounted therein, a 20 strut hingedly connected at one end to the main frame and provided with a keeper, a latch bar carried by the auxiliary frame and engageable with said keeper, and means whereby the keeper may be positively en-

gaged with one end of the auxiliary frame 25 when the latter is swung to an angular position relative to the main frame, as and for the purpose described.

2. A combined ironing-board and step-ladder embodying a main frame, an auxiliary frame pivotally connected thereto, a board hingedly connected at one end to one end of the main frame and provided on its face with a keeper projecting therefrom, and a latch bar carried by the auxiliary frame and engageable with said keeper, the auxiliary frame being provided at one end with a recess adapted to receive said keeper with the auxiliary frame swung to an angular position relative to the main frame, as 30 and for the purpose set forth.

In testimony whereof I hereunto affix my signature in the presence of two witnesses.

RICHARD C. LOWE.
